(57) **CLAIM**

The ornamental design for a display screen or portion thereof with graphical user interface, as shown and described.

DESCRIPTION

FIG. 1 is a front view of a first screen of a graphical user interface on a display screen or a portion thereof.

FIG. 2 is a front view of a second screen of the graphical user interface.

FIG. 3 is a front view of a third screen of the graphical user interface.

FIG. 4 is a front view of a fourth screen of the graphical user interface.

FIG. 5 is a front view of a fifth screen of the graphical user interface.

FIG. 6 is a front view of a sixth screen of the graphical user interface.

FIG. 7 is a front view of a seventh screen of the graphical user interface.

FIG. 8 is a front view of an eighth screen of the graphical user interface.

FIG. 9 is a front view of a ninth screen of the graphical user interface; and,

FIG. 10 is a front view of a tenth screen of the graphical user interface.

The outermost broken lines in the figures show a display screen or portion thereof and form no part of the claimed design. The other broken lines in the figures show portions of the graphical user interface that form no part of the claimed design.

(Continued)

The appearance of the graphical user interface sequentially transitions between the images shown in FIGS. 1-10. The process or period in which one image transitions to another forms no part of the claimed design.

1 Claim, 10 Drawing Sheets

FIG. 1

FIG. 2

What is COPD?

Chronic obstructive pulmonary disease (COPD) is a disease that restricts your oxygen flow, making it harder to breathe.

COPD is progressive. This means it slowly gets worse over time. COPD is not curable but is highly preventable.

Types of COPD

FIG. 3

FIG. 4

Diagnosis

Your doctor will ask you about your health history for a diagnosis. They will also run tests, such as spirometry. These tests measure lung function and their ability to help your breathing.
